UNITED STATES PATENT OFFICE.

JOHN L. NAIL, OF SANFORD, FLORIDA, ASSIGNOR OF ONE-HALF TO SAMUEL J. NORTON, OF TITUSVILLE, FLORIDA.

COMBINED TABLE.

No. 908,487.

Specification of Letters Patent.

Patented Jan. 5, 1909.

Application filed January 14, 1908. Serial No. 410,855.

To all whom it may concern:

Be it known that I, JOHN L. NAIL, a citizen of the United States, residing at Sanford, in the county of Orange and State of Florida, have invented new and useful Improvements in Combined Tables, of which the following is a specification.

This invention relates to a combined table and carrying case, and the object of the invention is to provide a device of this character primarily intended for salesmen in exhibiting their goods, and being so constructed as to be readily converted into a carrying case containing compartments for the reception of the goods exhibited and for the legs of the table.

With these and other objects in view the invention resides in the novel construction and combination of elements hereinafter fully described and claimed.

In the drawings, Figure 1 is a perspective view of my device showing the same in set up position as a table. Fig. 2 is a longitudinal section upon the line 2—2 of Fig. 1. Fig. 3 is a detail plan view of one of the corners of the device. Fig. 4 is a detail sectional view, illustrating the method of attaching the legs. Fig. 5 is a perspective view of the device closed to provide a carrying case, and Fig. 6 is a perspective view showing the compartments of the device opened and illustrating the method of holding one of the compartments in an upright position.

As illustrated in the accompanying drawings my combined table and carrying case comprises two sections or members 1 and 2, hingedly secured together as at 3 and comprising the tops 4, sides 5 and ends 6. One of the compartments, 2, is provided with a hinged closure 7 having a latch 8, by which it is held in position upon the compartment. The compartment 2 having the closure 7 is adapted for the reception of articles to be displayed when the device is used by salesmen, but it is of course understood that the device is not limited for the use of displaying goods, and the compartment may be employed as a receptacle for any desired articles.

The compartment 1 may be left open at its lower edge as illustrated in Figs. 2 and 6 of the drawings, and is primarily intended for the reception of the detachable legs of the

table, and also affords sufficient space for other articles when desired. When the compartments are folded together, as illustrated in Fig. 1 of the drawings, the closure 7 of the compartment 2 secures the articles within the compartment 1, though it will be understood that a closure may also be provided for the compartment 1 without departing from the spirit of this invention.

Upon the under surface of the tops 4, and at the outer corners of the compartments, are provided threaded spindles 9, adapted for the reception of the threaded ferrule 10 of the upper sections 11 of the leg members. The threaded spindles 9 are of a lesser size than the width of the sides of ends of the compartments, and immediately above the upper ends of the spindles, the compartments are provided with guiding and bracing elements 12 for the upper ferrules 10 of the leg sections. These guiding and bracing elements 11 are preferably constructed of a single strand of resilient wire, having their ends bent to provide teeth whereby they are secured to the sides and ends of the compartments, and having its intermediate portion formed into a loop of a circumference slightly greater than the ferrule 10 of the leg sections.

The legs of my improved device comprise each a series of sections, of a size approximately corresponding with the width of the compartment 1, wherein they are adapted to be received when the device is not used as a table. By reference to Fig. 2 of the drawings it will be noted that the lower portion of the upper leg sections 11 are reduced and threaded, while the upper portion of the lower sections are provided with an interiorly threaded ferrule 20 which is adapted to engage with the threaded projection 19 of the upper leg section when the sections are connected together. By this construction it will be seen that the leg members may be made of any required size whereby they may be conveniently fitted within the compartment 1. The guiding and bracing elements 12, encircling the upper section of the leg members 11, securely brace the legs in their engagement with the spindles and prevent wobbling or shaking.

The compartments 1 and 2 are each provided upon their sides near their hinged ends with a latch member 13, comprising a plate 14 having a perforation upon one of its

ends adapted for the reception of a retaining element 15, by which it is pivotally secured to the compartment. The opposite end of the latch is provided with an annular slit 5 or opening 16, adapted to engage a knob or button 17 upon the side of the opposite compartment. The latches 13 are adapted to be tightly secured upon the compartments, so as to be movable upon their pivots 15 10 only when manipulated by the operator, and whereby they may serve as an effective prop for holding one of the compartments in an angular position in relation to the other, whereby the contents of the raised compartment may be accessible without completely 15 lowering and spreading out both compartments. The latches also effectively secure the compartments in their spread out position when used as a table, as illustrated in 20 Fig. 1 of the drawings, as well as securing the compartments together in their position as illustrated in Fig. 5 of the drawings.

The outer ends 6 of the compartments are each provided with a suitable handle 18 25 whereby the device may be easily carried, and a lock 19 is provided for the compartments for securing them together and preventing opening except by the person holding the key.

30 From the above description it will be noted that I have provided a simple, cheap and strong combined table and carrying case, which may be readily converted into either a table or case as desired.

Having thus fully described the invention 35 what is claimed as new is:

A combined table and carrying case comprising two compartments hingedly secured together, a cover for one of the compartments, spindles adjacent the outer corners 40 of the compartments, bracing elements constructed of a strand of looped resilient wire above the spindles, latch members pivotally secured upon the outer sides of one of the compartments and near the pivoted end 45 thereof, said members each comprising a rectangular flattened plate having a slot, the opposite compartment being provided with a stud adapted to be engaged by the slot and whereby the compartments are secured when 50 employed as a table or as a carrying case and whereby one of the compartments may be retained in propped vertical position, sectional legs for the device, said sections having one of their ends provided with a ferrule 55 and their opposite ends provided with a reduced extension whereby the sections are secured together, and the ferrules of the uppermost sections adapted to engage the bracing elements and the spindles of the 60 compartments when the device is set up as a table.

In testimony whereof I affix my signature in presence of two witnesses.

JOHN L. NAIL.
